UNITED STATES PATENT OFFICE.

LONNIE J. PAYLOR, OF DANVILLE, VIRGINIA.

TOBACCO-HANGING MACHINE.

1,362,893.

Specification of Letters Patent. Patented Dec. 21, 1920.

Application filed April 22, 1919. Serial No. 291,829.

To all whom it may concern:

Be it known that I, LONNIE J. PAYLOR, a citizen of the United States, residing at Danville, in the county of Pittsylvania and 5 State of Virginia, have invented new and useful Improvements in Tobacco-Hanging Machines, of which the following is a specification.

This invention relates to machines for 10 hanging bundles or "hands" of tobacco, although, of course, it could be readily used in connection with the hanging of articles of a similar nature.

Tobacco, as received at the factory to be 15 put in condition for preservation until it is to be used for the manufacture of cigars, cigarettes, etc., is in bundles generally consisting of a dozen or more leaves tied together at their stems by a string, strip of 20 tobacco, or other suitable binding means, forming a head or butt for the bundle which in the trade are termed bands. These bundles must be put through a drying machine in which the natural moisture is removed from 25 the tobacco and a certain predetermined amount of artificial moisture is given the tobacco leaves after which they are suitably cooled and thereafter packed in hogsheads for shipment.

30 One of the main types of drying machines is known as the "stick machine" in which sticks, about three feet long are supported at each end by endless moving chains and are conducted through the machine, each of the 35 sticks being straddled by several bundles of tobacco.

I am aware that it has been heretofore proposed to mechanically hang stalks of tobacco by penetrating the stalk to form an 40 opening therein and thereafter placing the stalk upon a stick. I am also aware that it has been proposed that the same operation be performed upon "hands" of tobacco, but, so far as I am aware, I am the first to devise 45 a machine which preliminarily prepares the "hand" for hanging, by fluffing the same, and then hangs the "hand" upon a stick.

An objection to the present method employed for stringing bundles upon laths is 50 the fact that there is no economical and satisfactory method for suitably moistening the "hands" of tobacco prior to opening them up and placing them upon the laths. 55 As a result, the leaves being often very dry and brittle, there is a considerable loss of

tobacco which it is of course desirable to eliminate.

Furthermore, when hands of tobacco are put through a drying machine it is necessary that their leaves be separated and that the hands be in a rather fluffy condition in order that the artificial heat and moisture may readily penetrate between them and have the desired effect upon every leaf of 60 the hand. To permit this it is necessary, when manually hanging the bundles of tobacco, to shake and beat them in order to obtain the above mentioned fluffy condition of the hand in which the leaves are separated. It should be obvious that this is a rather rough treatment and when the tobacco is very dry results in the breaking and tearing of the tobacco leaves which it is 65 of course desirable to overcome.

The general object of my invention is to provide a machine which will automatically place the hands upon their laths. In seeking to attain this object I also have other aims such as the satisfactory moistening of the 70 hands prior to stringing, the formation of an opening among the leaves and the fluffing of the bundles without the above mentioned shaking and general harmful treatment of the bundle incident to manual hanging.

The above, and other objects of my invention which will become apparent as the description proceeds, I accomplish by providing a machine which may be briefly described as follows:

There is provided, first, a primary conveyer for "hands" of tobacco which conducts the "hands" through a steam box or other suitable moistening mechanism and then onward to a secondary conveyer which receives the "hands" and carries them past a divider and spreader, the former partially dividing the bundle longitudinally, the spreader fluffing the bundles and opening them up through their longitudinal center, 95 the bundles being thereafter held in this opened condition until they reach a point of discharge where they are dropped upon laths successively placed in position to receive the opened up bundles.

Reference will now be had to the accompanying views, it being understood that the machine shown therein is merely one of many types in which my invention could be embodied.

In these drawings—

Figure 1 is a side elevational view of a

portion of the machine, the primary conveyer being shown in longitudinal section;

Fig. 1^a is an elevation of the same side of the machine showing the continuation 5 thereof;

Fig. 2 is a vertical cross-section on the line 2—2 of Fig. 1^a;

Fig. 3 is a vertical cross-section on the line 3—3 of Fig. 1^a;

10 Fig. 4 is a plan view of a portion of the compressing guides shown in Fig. 1^a;

Fig. 5 is a plan of a portion of the primary conveyer, and

15 Fig. 6 is a detail view showing the divider and spreader for the bundles.

Referring to the drawings more in detail, it should be understood that while a specific embodiment of my invention is shown therein, and that while the machine is described 20 as being used in connection with bundles of tobacco, the scope of my invention is not limited to use with "hands" of tobacco nor is it confined to the specific features of construction disclosed in the accompanying 25 drawings, since my invention is shown therein merely by way of illustration and numerous changes in construction could well be made within the purview of my inventive idea.

30 The machine shown in the drawings naturally divides itself into three distinct elements; a primary conveyer A, a secondary conveyer B and a stick or lath carrier C adapted to carry laths to the discharge point 35 E of the secondary conveyer B for the purpose of receiving the opened up bundles of tobacco discharged from the secondary conveyer at this point.

The primary conveyer A comprises three 40 parallel endless chains a^1 , a^2 , a^3 , extending around sprockets upon shafts 1 and 2, each chain being provided with spaced lugs a^4 for the purpose of receiving the "hands" 45 of tobacco which are laid across the chains in the horizontal plane as shown in Fig. 5. As will be observed from Fig. 1, this primary conveyer passes through a steam box 3 having located therein upper and lower steam pipes 5, 6, provided with jets for the 50 purpose of moistening "hands" of tobacco as they pass therethrough. Steam may be conducted to the jets from any suitable source of supply, the pipes being provided with manually operable valves 7 to regulate 55 the supply of steam to the jets, and the steam box may be supported in any suitable manner, in the present instance it being shown as secured to a frame 8 in which is located the sprocket shaft 2.

60 As indicated in Fig. 1, the primary conveyer at its end adjacent the shaft 2 meets the secondary conveyer B, which consists of two endless belts b^1 , b^2 , the latter belt at the point where the conveyer meets the primary 65 conveyer being run around an idler 9 upon

a stub shaft 10. This idler is located between the two chains a^1 , a^2 , of the primary conveyer and hence the lower belt b^2 receives the bundles of tobacco adjacent their tied ends, the bundles being always laid 70 upon the primary conveyer chains with their tied ends adjacent the chain a^1 . This method of placing the "hands" upon the conveyer is necessary for the bundles must always be received by the secondary conveyer 75 in such a manner that their main body portion hangs from the side of the belt. After being received by the belt b^2 of the secondary conveyer, the "hands" are carried along and pass between the two belts 80 b^1 , b^2 , the former passing around a sheave 11 upon a shaft 11^a located above and slightly to the rear of the lower belt idler 9. It should be observed that the belts are both 85 angularly and rectilinearly movable and after the reception of the "hands" are given a quarter turn by the angularly disposed idler 13 supported from a bracket 12, which bracket is located upon an extension of the frame 8. The belts of the secondary conveyer 90 with the bundles held between them by their bound ends or butts and having been given a quarter turn by the idler 13 about an axis parallel with their path of travel, pass onwardly through a main frame 95 14 shown in Fig. 1^a.

The frame 14 comprises a plurality of vertical legs 15 having longitudinal frame braces 16, 17, running along the top and bottom of the frame, the frame being transversely strengthened by cross-members 18. In order to press together the two belts b^1 , b^2 , as they pass through the frame, there are provided two guide bars 20, 21, yieldably urged together by compression springs 22. 105 Referring to Figs. 3 and 4, the guide bars are each provided with a plurality of longitudinally extending grooves 23 upon their inner surfaces and there are located upon the same surfaces within semi-circular recesses a number of idlers 24 disposed in staggered relation, the idlers being journaled 110 upon pins 25 within these recesses. By thus disposing the idlers 23 in contact with the belts the friction of the belts with the guide 115 bars is considerably reduced and the grooves 23, permitting circulation of air between the belts and the guides, keep to a minimum the heat between the guide bars. The guide bars are supported upon horizontal arms 120 26 extending inwardly from the vertical legs 15 of the frame, the arms also serving to support abutment blocks 27 for the compression springs 22 which urge followers 28 against the rear faces of the guide 125 bars.

From the above description it should be observed that while the bundles of tobacco lie in the horizontal plane when they are received by the secondary conveyer B, they 130

are turned about an axis parallel with the path of travel of the secondary conveyer belts, and these belts being pressed together by the yielding guides 20, conduct the 5 "hands" through the machine.

In order to provide for the opening up of the "hands" there is located beneath that portion of the secondary conveyer which travels in a vertical plane between the 10 guides within the frame 14, a divider and spreader shown more clearly in Figs. 2, 3 and 6. In the present embodiment of my invention I have shown the spreader as comprising a plurality of supports 29, each support having two longitudinally diverging legs 30, (Fig. 6) meeting at a point 32 just beneath the traveling belts b^1, b^2 . The diverging legs 30, of each support carry at their point of meeting a bar 33 running 15 longitudinally of the machine within the frame 14 and having at its end adjacent the front of the frame 14 (shown at the left of Fig. 6) a removable spear point 33^a held within a socket at the tip of the bar 33 by 20 means of a set screw indicated at 34. At a point to the rear of the spear 33^a is located a downwardly and rearwardly extending dividing bar 35 which at 36 is bent upwardly to the bar 33. The spear 33^a is adapted to 25 penetrate a bundle at a point just below the bound end, forming an opening between the leaves. The bar 35 being in the same vertical plane as the spear divides the bundle from the point of penetration of the spear 30 toward its base as it is carried along by the 35 conveyer. In order to provide for the opening up of the bundle, the spreader has attached thereto parallel bars 37 running longitudinally of the frame 14 and supported at vertically spaced points along the 40 diverging legs 30, of the brackets upon which rests the bar 33. At a point adjacent the front supporting bracket 29 these bars have inwardly and upwardly turned portions 45 37^a running to points 37^b slightly to the rear of the spear 33^a, thus producing a construction in which the portions 37^a are adapted to spread apart the portions of the bundle on each side of the dividing bar 35. 50 As the bundles of tobacco are carried along by the belts b^1, b^2 , they are engaged by the spear 33^a at a point below their bound ends, which it will be recalled are held between the two belts, the spear penetrating the 55 bundles which when carried along are longitudinally divided by the dividing bar 35. The two portions of the hand thus formed on each side of the divider 35 are then spread apart by the inwardly and upwardly conveying bars 37^a, the bundles being held in this opened condition by the parallel portions 37 of those bars running longitudinally of the frame 14. It might be well to 60 remark in this connection that it is for the purpose of preparing the "hands" for the

spreader that the steam box 3 is provided and the "hands" passed therethrough prior to being disposed upon the secondary conveyer. The "hands" as received prior to being placed upon the laths are often very dry 70 and brittle and their leaves are frequently matted together. It is well known in the treatment of tobacco that heat and moisture will not only soften the leaves but there is a tendency for bundles of tobacco to open up 75 and the leaves thereof to separate when attacked by moisture and heat. Hence, when the bundles of tobacco pass through the steam box 3 the steam from the pipes 5 has the above noted effect upon them and, consequently, when they reach the spear 33^a and the divider 35 the bundles are readily divided and opened up. While the steam box is not necessary at all times it has been 80 found that it materially aids in the operation of a machine, particularly when the tobacco is very dry and brittle, as when tobacco in that condition is carried to the spear the latter has a tendency to pierce the leaves or stems of the tobacco and to split them. 85 Furthermore, when the leaves of the bundles are matted together, whole bundles or large parts thereof will often be broken off if not moistened prior to their conveyance to the spreader. After being divided by the spear 90 33^a and divider 35 the portions of the bundles on each side of the divider 25 are moved apart by the inwardly and upwardly extending portions 37^a of the bars 37 running longitudinally of the frame 14, and 95 while being held in this spread condition by the parallel portions of the bars 37 extending through the frame 14 at a point E are discharged upon laths S supported at 100 this point for the reception of the opened 105 up bundles.

Here it should be observed that the construction above described not only divides the hands below their heads and through their longitudinal center, and spreads apart 110 the two sections into which the hand is divided, but it also satisfactorily fluffs the bundle and causes relative movement of the leaves without the shaking and beating against some object as is at present necessary in manual hanging. As before stated, this shaking of the bundle and the striking of the same against an object is necessary when hanging the bundles by hand in order 115 to cause relative movement and separation of the several leaves so that the heat and moisture of the drying machine may penetrate through the entire bundle. By the construction above described, I have found that this fluffing of the bundle and the relative 120 movement of the leaves is obtained without the shaking and necessarily rather rough handling incident to the manual hanging of the tobacco. In my machine the fluffed condition is brought about not only by the ac- 125 130

tion of the steam box which of course causes a slight separation of the leaves but is primarily due to the construction of the spreader. After the spear 33^a penetrates the 5 bundle below its bound end, the divider 35 continues this division from the point of penetration downwardly to the base or leaf end of the bundle and, as the latter is carried along, the downwardly and rearwardly 10 inclined portions 37^a of the bars 37 spread apart its portions on each side of the divider 35. This operation has been described but it should be pointed out that as the two 15 sections of the bundle are moved apart the leaves in each section move relative to each other and are therefore separated should they be matted together. It should also be noted that the idlers 24 are disposed in staggered relation and as the hands are carried 20 between the guide bars 20 and pass each of the idlers the guides are slightly moved in lateral direction, thus causing a movement of the leaf portion of the hand in a lateral direction relative to the bar 33 and the parallel bars 37, which retain the hand in spread 25 condition. This lateral movement is noticeable particularly as the hands reach the points where the idlers 24 are located, and takes place in alternately opposite directions 30 because of the fact that the idlers are staggered as shown. The lateral movement of the leaf portion of the hand against the bars 33 and 37 thus causes relative movement of the individual leaves and continues 35 the fluffing operation which was started by the spear and spreaders. Thus the fluffed condition obtained in the manual hanging of these bundles by the shaking and beating of the bundle is obtained in my machine 40 in a manner calculated to avoid breaking and tearing of the leaves.

In order to place laths at the discharge point E (Figs. 1 and 1^a) there is provided a stick conveyer C consisting of an endless 45 chain *c*¹ running from a sprocket 39 on the shaft 40 located beneath the support 8 to a larger sprocket wheel 41 upon a shaft 42 having a bearing in a vertical bearing arm 43. The chain *c*¹ has at suitable intervals 50 lugs *c*² which serve as drags for the laths which receive the opened up bundles. The chain may be of an adjustable nature so that links may be removed from and added thereto in order that the distance between 55 the lugs *c*² may be varied in accordance with the length of the stick or lath to be used. In order to accommodate the device to variations in the length of the stick conveyer chain *c*¹, the bracket support 43 for the 60 sprocket shaft 42 is rendered adjustable to and from the main frame 14 by securing the same upon a movable base 44. The stick conveyer chain travels through a guide 45 of any suitable construction in the present instance shown as a channel bar and the laths

may be placed upon the chain at a point adjacent the sprocket 39.

From the above it should be clear that as the "hands" of tobacco reach the end of the frame 14, having been opened and held in opened condition while they pass therethrough by the bars 37, they are disposed upon laths at a point E where the stick conveyer and the secondary tobacco conveyer meet. As they are dropped upon the sticks 75 and straddle the latter in the manner clearly shown in the drawings, the sticks are removed from the conveyer chain *c*¹ and may then be placed in the drier.

The conveyers A, B and C may be driven 80 in any desired manner but in the embodiment of my invention shown in the accompanying drawings, power is applied to a horizontal shaft 45 having bearings in brackets 46 located at the end of the frame 85 14. Movement is imparted to the secondary conveyer from the shaft 45 through the bevel gears 48 thereon which mesh with crown gears 49 upon two vertical shafts 50, 51 having bearings in brackets 53 on the 90 main frame 14 and having secured to their lower ends the conveyer belt sheaves 52. Movement is thus imparted to the secondary conveyer belts and by connecting the pulley 11 of the upper belt *b*¹ with the shaft 40 95 through a turned belt 55 shown in Fig. 1, motion is given to the stick conveyer chain *c*¹. The above mentioned connection between the drives of the stick conveyer C and the secondary conveyer B for the bundles maintains a fixed relation between the speed of the two conveyers at all times.

The primary conveyer A may be driven in any desired manner but I have found it desirable to drive the same from a source 105 of power separate from that which moves the secondary conveyer B and stick conveyer C, as it is advisable at times to vary the speed of the primary conveyer according to the number of bundles which one may wish 110 to place upon each lath. As will be obvious from inspection of the several views the number of bundles which are deposited upon each of the sticks as they are conveyed to the discharge point E of the secondary conveyer will be directly proportionate to the speed of the primary conveyer A and it is to obtain a variation in the number of "hands" placed upon each stick that a separate drive 115 for the primary conveyer A is desirable. 120 This drive may be applied either to the shaft 1 or to the shaft 2, as is desirable.

From a casual reading of the above specification in connection with the accompanying drawings, it should be apparent that I 125 have provided a machine which will satisfactorily hang bundles of tobacco upon laths and will accomplish this result to the saving of a great amount of labor which it has heretofore been necessary to employ when 130

manually hanging tobacco. It should be borne in mind that I have described in this specification but one embodiment of my invention and that various changes could be 5 made in the machine described without departing from the scope of my inventive idea. For instance, the primary conveyer could easily be eliminated, the "hands" of tobacco being placed directly in the secondary conveyer; or the lath conveyer could be eliminated and the laths held at the discharge point E by operators or supported at this 10 point in a stationary manner by a fixed support from which the laths might be moved as they are filled. It should be clear therefore that the machine herein described is merely an illustration of my invention and that various other means might be employed for carrying into operation the inventive 15 idea, the essential feature of which is the provision of means for preliminarily preparing and placing "hands" upon sticks for introduction into the drying machine or for treatment into any other machine in which 20 it may be desirable to place the bundles.

What I claim is:

1. In a machine of the class described, means for supporting a hand of tobacco, means for partially dividing the hand below its tied end into separated portions and partially opening the leaves, and means for causing relative movement between said supporting means and said dividing means.
2. In a machine of the class described, means for supporting a hand of tobacco, means for dividing the hand from a point below its tied end to its leaf end into two separated portions and partially opening the leaves, and means for causing relative movement between said supporting means and said dividing means.
3. In a machine of the class described, means for conveying a hand of tobacco, and means for dividing the hand being conveyed from a point below its tied end to its leaf end into two separated portions and partially opening the leaves.
4. In a machine of the class described, endless belt conveying means adapted to carry a hand of tobacco held by its tied end in pendent position, and means adjacent the path of travel of said conveying means in one direction for dividing the hand from an intermediate point to its leaf end and partially opening the leaves.

5. In a machine of the class described, a pair of facing endless belts adapted to engage and convey hands of tobacco in pendent position between them, said belts having a path of travel in a horizontal plane, means below said horizontal path of travel adapted to divide the hands from points below their tied ends to their leaf ends and partially opening the leaves.

6. In a machine of the class described,

means for conveying hands of tobacco supported by their tied ends with their leaf portions hanging in pendent position, means positioned in the path of travel of the hands for dividing the hands from intermediate points to their leaf ends and partially opening the leaves, and means for causing relative movement between said hands and said dividing means transversely of said path of travel of the hands to cause 75 a relative movement of the adjacent leaves of the hand.

7. In a machine of the class described, means for conveying hands of tobacco supported by their tied ends with their leaf portions hanging in pendent position, means positioned in the path of travel of the hands for dividing the hands from intermediate points to their leaf ends and partially opening the leaves, and means for 80 moving said hands transversely of said path of travel and relatively to said dividing means to cause a relative movement of the adjacent leaves of the hand.

8. In a machine of the class described, a 90 conveyer for hands of tobacco having a point of reception and a point of discharge for the hands, means operative during the conveyance of the hands for dividing the hands and maintaining them divided from 95 intermediate points to their leaf ends and partially opening the leaves, and means for supporting laths at said point of discharge to receive the divided hands.

9. In a machine of the class described, a 100 conveyer for hands of tobacco having a point of reception and a point of discharge for the hands, means operative during the conveyance of the hands for dividing the hands and maintaining them divided from 105 intermediate points to their leaf ends and partially opening the leaves, and means for successively positioning laths at said point of discharge for receiving the divided hands.

10. In a machine of the class described, a 110 conveyer for hands of tobacco having a point of reception and a point of discharge for the hands, means operative during the conveyance of the hands for dividing the hands and maintaining them divided from 115 intermediate points to their leaf ends and partially opening the leaves, and means for supporting laths at said point of discharge and moving them lengthwise past said point of discharge to receive said opened bundles. 120

11. In a machine of the class described, a conveyer for hands of tobacco having a point of reception and a point of discharge for the hands, means operative during the conveyance of the hands for dividing the 125 hands and maintaining them divided from intermediate points to their leaf ends and partially opening the leaves, and a conveyer for successively positioning laths at said point of discharge and moving said 130

- laths lengthwise past said point of discharge to receive said opened hands thereon.
12. In a machine of the class described, a conveyer for bundles of tobacco adapted to discharge bundles at a predetermined point, means for forming an opening in the bundles carried by said conveyer prior to their discharge, and means for supporting laths at the point of discharge of the conveyer and moving said laths lengthwise past said point whereby the bundles are received thereon in spaced relation.
13. In a machine of the class described, means for conveying hands of tobacco, means for moistening the hands, and means for dividing the moistened hands from intermediate points to their leaf ends and partially opening the leaves.
14. In a machine of the class described, means for conveying hands of tobacco having a point of reception and a point of discharge, means for moistening the hands, means for dividing the moistened hands from intermediate points to their leaf ends and partially opening the leaves, and means for supporting laths in position at said point of discharge to receive said divided hands.
15. In a machine of the class described, in combination with a conveyer adapted to carry hands of tobacco supported by their tied ends with their leaf ends hanging loosely in pendent position, means for dividing the hands from intermediate points to their leaf ends and partially opening the leaves, said means comprising a portion adapted to penetrate the hand below its tied end, a portion for dividing the hand from the point of penetration toward the leaf end, and a portion for moving apart the two portions of the hand on opposite sides of the line of division.
16. In a machine of the class described, means for opening up hands of tobacco comprising a pointed member for penetrating the bundle, a member rearwardly and downwardly inclined from a point adjacent said pointed member, and longitudinally diverging spreaders extending rearwardly from points adjacent said pointed member.
17. In a machine of the class described, means for supporting a hand of tobacco by its tied end with its leaf end free and disengaged, means for forming an opening in the hand below its tied end, means for maintaining said opening in the hand, means for supporting a lath in position to receive said opened hand, and means for moving said hand supporting means to carry said opened hand to said lath.
18. In a machine of the class described, means for supporting a hand of tobacco, means for forming an opening in the hand between the leaves thereof and causing a relative movement of the individual adjacent leaves to create a fluffed condition for the hand, and means for causing a relative movement between said supporting means and said opening means.
19. In a machine of the class described, means for conveying a hand of tobacco, and means adjacent the path of said conveying means for forming an opening in the hand being conveyed and causing a relative movement of the adjacent leaves to create a fluffed condition of the hand.
20. In a machine of the class described, means for supporting a hand of tobacco, means for penetrating the hand below its bound end and adapted to press apart the two portions of the hand on each side of the opening thereby relatively moving the adjacent leaves of the hand, and means for causing relative movement between the supporting means and said penetrating and opening means.
21. In a machine of the class described, means for conveying hands of tobacco in spaced relation by holding their tied ends with their leaf portions free, means disposed adjacent the path of said conveying means adapted to penetrate the hands below their tied ends and to press apart the two portions of the hand on opposite sides of the opening thus formed thereby relatively moving the adjacent leaves of each portion of the hand.
22. In a machine of the class described, means for conveying hands of tobacco in spaced relation by holding their tied ends with their leaf portions hanging freely in pendent position, means disposed in the path of said conveying means adapted to penetrate the hands below their tied ends and to press apart the two portions of each hand on the opposite sides of the opening thus formed thereby relatively moving the adjacent leaves of each hand, and means for supporting laths in position to receive the hands from said conveying means.
23. The method of relatively moving the adjacent leaves of a hand of tobacco which consists in supporting the hand with its leaf portion disengaged, forming an opening in the hand below its bound end, and exerting lateral pressure in opposite directions from said opening thereby moving the two portions of the hand in opposite directions and relatively moving the adjacent leaves of each portion.
24. The method of relatively moving the adjacent leaves of a hand of tobacco which consists in supporting the hand by its tied end with its leaf portion hanging freely, forming an opening in the hand below its bound end, and exerting a lateral pressure in opposite directions from said opening thereby moving the two portions of the hand in opposite directions and relatively moving the adjacent leaves of each portion.
25. The method of relatively moving the adjacent leaves of a hand of tobacco which consists in supporting the hand by its tied end with its leaf portion hanging freely, forming an opening in the hand below its bound end, and exerting a lateral pressure in opposite directions from said opening thereby moving the two portions of the hand in opposite directions and relatively moving the adjacent leaves of each portion.

adjacent leaves of a hand of tobacco which consists in supporting the hand by its bound end with its leaf portion hanging freely, forming an opening in the hand below its bound end, exerting an outward pressure in opposite directions from said opening to spread apart the two portions of the hand

thus formed, maintaining a member in said opening and producing a relative movement between said hand and member in a direction transverse to the member. 10

In testimony whereof I have hereunto set my hand.

LONNIE J. PAYLOR.
